(57) **CLAIM**

The ornamental design for a bowl, as shown and described.

DESCRIPTION

FIG. 1 is a top, front, right perspective view of a bowl showing our new design;
 FIG. 2 is a front view thereof, wherein the rear view is a mirror image of FIG. 2;
 FIG. 3 is a right side view thereof, wherein the left side view is a mirror image of FIG. 3;
 FIG. 4 is a top view thereof;
 FIG. 5 is a bottom view thereof;
 FIG. 6 is a cross-sectional view at 6-6 in FIG. 4 thereof; and,
 FIG. 7 is a cross-sectional view at 7-7 in FIG. 1 thereof.
 The contrast in shading shown in FIGS. 5 and 6 represents a contrast in appearance only and does not represent any particular color, material, texture or finish.
 The broken lines depicting the remainder of the bowl show features that form no part of the claimed design.
